UNITED STATES PATENT OFFICE

155,045

DESIGN FOR A TOY TOP

Harry A. Spyros, Detroit, Mich., assignor to Spyro Toy Company, Detroit, Mich., a partnership

Application July 31, 1947, Serial No. 140,648

Term of patent 14 years

(Cl. D34—15)

To all whom it may concern:

Be it known that I, Harry A. Spyros, a citizen of the United States of America, residing at Detroit, in the county of Wayne and State of Michigan, have invented a new, original, and ornamental Design for a Toy Top, of which the following is a specification, reference being had to the accompanying drawing, forming part thereof.

Fig. 1 is a side elevational view of a toy top, showing my new design;

Fig. 2 is a bottom plan view of the top shown by Fig. 1; and

Fig. 3 is a top plan view of the top shown by Fig. 1.

I claim:

The ornamental design for a toy top, as shown.
HARRY A. SPYROS.
